PHOTOGRAPHIC REPRODUCTION OF
DESIGNS IN DISTORTED FORMSKenneth J. Snyder, Toledo, Ohio, assignor to
Owens-Illinois Glass Company, a corporation
of Ohio

Application January 19, 1949, Serial No. 71,673

17 Claims. (Cl. 95—73)

1

My invention relates to photographic reproduction methods and apparatus. It provides a method and means for photographically reproducing designs in a modified or distorted form. Such designs are of utility in the preparation of decorating screens for use in the art of decorating conical or frusto-conical surfaces, as for example, the tapered shoulders of round bottles.

At the present day, screen decorating methods are extensively used for applying lettering and decorative designs to the cylindrical bodies and tapered shoulders of round bottles. In decorating the cylindrical body surfaces of the bottles, a decorating screen is moved in a straight line over the surface to be decorated while the bottle is in rolling contact with the screen. The ceramic decorating material is forced through the screen by means of a squeegee. If the tapered shoulder surface of the bottle is to be decorated, a screen bearing the design may be moved over such surface in an arc-shaped path while the bottle rotates about its axis, thereby permitting the design to be transferred in undistorted form.

A second method of decorating such a tapered shoulder consists in moving the screen in a straight line path while in rolling contact with the tapered shoulder. This second method is particularly desirable from an operating standpoint but the design as thus applied to such surface is distorted. In order to overcome this objection it has been the custom for the artist to reproduce the design in a distorted form such that when applied to the decorating screen and used with a straight line method of transfer, the design appears on the tapered surface of the bottle in undistorted form. Such reproduction of the design by the artist in its modified or distorted form is accomplished by the manual transfer of reference points by means of coordinates. This is a tedious and time-consuming operation and an object of the present invention is to provide a novel form of apparatus for mechanically and photographically reproducing the design in its modified or distorted form to replace such manual transfer method.

A further object of the invention is to provide a simplified method of reproducing designs in modified form adapting them for use when the design is to be applied to the tapered shoulders of bottles on which designs are also to be applied to the cylindrical bodies. The designs then may be applied to both the said body and shoulder of the bottle simultaneously by the straight line method in a single operation and with comparatively simple apparatus.

2

A further object of the invention is to provide an apparatus for mechanically and photographically producing a distorted straight positive from a radius negative for the application of ceramic paint to the tapered shoulder of a bottle in a design which is undistorted. The invention provides means for producing a positive of the desired design in a modified or distorted form on a contrast film from which a decorating screen is made that can be used for decorating by the straight line method, thereby permitting the tapered shoulder and cylindrical body of the bottle to be decorated simultaneously with an automatic decorating machine.

5 15 A further object of the invention is to provide a means by which a distorted positive of the character indicated, made from an undistorted negative, may be used to photographically reproduce the design in undistorted form.

10 20 Other objects of the invention will appear hereinafter.

Referring to the accompanying drawings:

Fig. 1 is a plan view, with parts broken away, of a photographic reproducing apparatus for use in practicing my invention.

25 30 Fig. 2 is a sectional side elevation of the same.

Fig. 3 is a fragmentary cross-sectional elevation at the line 3—3 on Fig. 2, showing the means for exposing the sensitized film.

Fig. 4 is a diagrammatic view of a bottle, and means for decorating the body and shoulder of the bottle.

35 40 Fig. 5 is a perspective disassembled view of the parts shown in Fig. 3.

Fig. 6 is a view of a negative showing the design in its undistorted form.

Fig. 7 is a view of a distorted positive photographically reproduced from the negative of Fig. 6.

45 50 Fig. 8 is a view similar to Fig. 3 showing means by which the negative (Fig. 6) in undistorted form may be reproduced from the distorted positive (Fig. 7).

Referring to Figs. 1 and 2, the apparatus comprises a cabinet 10 including a horizontal top 11, front wall 12, rear vertical wall 13 and a bottom 14 hinged at 15 to the rear wall. Within the cabinet is a gear case 16 carried by a bracket 17 mounted for forward and rearward adjusting movement along the under surface of the cabinet top wall 11. The bracket is secured to the top 11 by screw bolts 18 which extend through slots 19 permitting adjustment of the gear case. A vertical shaft 21 journaled in the case 16 has keyed thereto a worm gear 22 driven by a worm

23 on an extensible shaft comprising telescopically connected sections 24 and 25, the latter journaled in the front wall 12. A hand crank 26 is attached to the shaft for driving the worm gearing and thereby rotating shaft 21.

Mounted on the top of the cabinet at the rear end thereof is a frame 27, comprising front and rear rails 28 and 29, on which is mounted a carriage 31 for horizontal reciprocating movement.

A straight rack bar 32 is bolted to arms 33 attached to, and extending forwardly from the carriage 31. The rack bar is formed with rack teeth 38 which mesh with the gear teeth 34 of a segmental gear 35 secured to and concentric with the shaft 21.

A sensitized photographic film 36 on which is to be produced the distorted positive design 37 (Fig. 7), is mounted on a pair of arms 38 and 39 on the carriage 31. The arm 38 is secured by screws 41 to the carriage. The arm 39 is adjustably connected to the carriage by means of a clamping screw 42 extending through a slot 43 in the arm 39. The film 36 may be removably attached to the arms 38, 39 by strips 44 of adhesive tape.

A film 45 on which is a developed negative 46 of the design, in undistorted form, is supported directly beneath and in juxtaposition to the film 36. The means for supporting the film 45 comprises a pair of radial arms 47 carried by clamping disks 48 secured to the shaft 21, the arms 47 being rotatively adjustable relative to the disks 48 to accommodate films 45 of different lengths. The film 45 may be attached to the arms 47 by means of adhesive tape in the same manner as the film 36 is secured.

The sensitized film 36, mounted as above described, is moved in a straight line with the carriage 31, and is so positioned on the supporting arms 38 and 39 that the center line 51 (Figs. 1 and 7), midway between the top and bottom of the design, is directly over and parallel with the rack teeth on the rack bar 32. The negative design 46 as a whole (Fig. 6) as shown is curved or arc-shaped, and the film 45 is so positioned on the arms 47 that the longitudinal center line or arc of curvature 52, midway between the upper and lower margins of the design 46, is directly over the gear teeth 34 of the segmental gear 35. That is, the center line of the design is an arc concentric with the shaft 21 and having the same radius of curvature as the gear 35.

The means for exposing the sensitized film 36 comprises an electric lamp 53 mounted within a light tight shield 54 attached to the under surface of the cabinet top 11. The light is transmitted upwardly through an aperture 55 in the wall 11 and a passageway 56 formed by the walls of a film supporting member 57 or cap mounted on the cabinet. The channel 56 terminates at its upper end in a narrow horizontal slit 58. The negative film 45 and the sensitized film 36 directly thereover are held together and in contact with the support 57 by a pressure roll 59 journaled in an arm 61. The arm 61 is connected by a pivot 62 to a bracket 63 on the cabinet, permitting the roll to be lifted. The light slit 58, which is perpendicular to the rack bar 32, is of a length to extend entirely across the design which is to be reproduced.

Operation

The operation of reproducing the design from the negative 46 takes place in a dark room and is as follows.

The sensitized film 36 and the fixed negative film 45 are attached respectively to the carriage 31 and the radial arms 47 as above described and the segmental gear 35 is rotated by the hand crank 26 to position the films with the slot 57 at or beyond one end of the design 46. The lamp 53 is then lighted and the hand crank turned to rotate the segmental gear 35 and thereby move the negative film 45 forward in its own plane and in an arc-shaped path, and simultaneously move the rack 32 and sensitized film 36 lengthwise in a straight path. The light passing through the slot 58 is transmitted through the transparency 45 bearing the negative design 46, thereby exposing the sensitized film 36 as the two films transverse the light slit 57. As the negative 45 is moving in an arc while the film 36 is moving in a straight line during such exposure, the reproduced design 37 is modified or distorted owing to the relative movement of the films during such exposure. The portion of the negative design below the line 52 (as viewed in Fig. 6) will move at a somewhat higher speed than the film 36 so that the corresponding reproduced portions of the design on the film 36 are shortened or contracted. In like manner the portions of the design above the center lines 51 and 52 are lengthened in the reproduced design 37. The net result of the reproduction of the arc-shaped design 46 in this manner is a modified or distorted design of the form shown in Fig. 7.

After the exposed film 36 has been developed and fixed, the design 37 is reproduced on a screen 65 (Fig. 4) and is then used for decorating the tapered or frusto-conical shoulder surface 66 of a bottle 67. The screen 65 is moved in a straight line while the bottle is rotated about its longitudinal axis with the surface 66 in rolling contact with the screen. The design reproduced on the tapered surface 66 is a modified or distorted reproduction of the design 37 but such distortion is the reverse of the distortion in the design 37 produced from the undistorted negative design 46, so that the design on a bottle is an undistorted reproduction of the design 46.

Fig. 8 illustrates a device by which the design 46 (Fig. 6) may be reproduced in undistorted form from the distorted positive 37. The lamp 53 is mounted in a casing 68 over the support 57, the casing 68 being provided with a light slit 69. The film 36 which has been developed and fixed with the distorted positive design 37, is in this instance placed over a sensitized film 45a and the latter exposed in the manner above described. When the exposed film has been developed and fixed, the result is a duplicate of the undistorted negative design as shown in Fig. 6.

The method herein disclosed is not limited to the use of radiation within the visible spectrum. Ultraviolet radiation or actinic radiation generally may be employed. The term "light" as herein used is intended to cover all such radiation.

Modifications may be resorted to within the spirit and scope of my invention.

I claim:

1. The method of photographically reproducing a design in a modified or distorted form, which method comprises superposing a sensitized sheet and a sheet consisting of a transparency bearing said design, applying to a restricted area of the design bearing sheet, a beam of light, said area being in the form of a narrow strip extending across the design bearing sheet, moving the latter relatively to the light beam in a direction transverse to that in which the said light strip

extends and thereby exposing the entire design progressively to the light beam, moving the sensitized sheet concurrently with the movement of the design and with the portions of said sheets which cross the light beam strip at a predetermined point in said strip, both moving in the same direction and at the same speed while passing said point, and shifting the relative positions of the two sheets by an angular relative movement of the sheets maintained throughout the said exposure of the design.

2. The method of photographically reproducing a design in a modified or distorted form which comprises superposing a transparency bearing the said design and a sensitized film, said transparency and film each being in the form of a sheet, applying to a restricted area of said transparency, a beam of light in the form of a narrow beam extending across the transparency, moving said superposed sheets simultaneously and with the portions of said sheets exposed to said beam moving while exposed, in the same direction, the said direction of movement being perpendicular to the said direction in which the beam is extended, the movement of one said sheet being in a straight path and of the other in an arc-shaped path, thereby exposing the sensitized sheet and impressing thereon a modified form of design, and thereafter developing and fixing the sensitized film.

3. The method which comprises superposing a design and a photographically sensitized film, exposing the design to actinic radiation confined to a narrow strip area of the design, and progressively advancing the area of exposure while maintaining such restriction and thereby exposing the entire area of the design and concomitantly said film to said radiation, causing a slight relative angular movement of the said film and design during the progression of said exposure by which the design in modified form is impressed on the film, and thereafter developing and fixing the exposed film.

4. The combination of a photographically sensitive film, a transparency bearing a design, means for supporting said film and transparency in superposed relation, a light source, means providing a narrow elongated slit through which light from said source is transmitted and directed against a correspondingly shaped area of the transparency, means for moving the said transparency and film transversely of said slit while in said superposed relation and thereby causing the area of exposure to advance over the transparency, thereby subjecting the transparency progressively to the light and exposing the film to the light transmitted through the transparency, and means for guiding the transparency in an arc-shaped path and said film in a straight path during said exposure.

5. The combination of a transparent sheet bearing a design, a photographically sensitized film, a carriage on which said film is mounted, a support on which said transparent sheet is mounted, with said sheet and film parallel and close together in superposed relation, an electric lamp, an enclosure therefor, the walls of the enclosure being formed with an elongated slit, means for driving the carriage in a straight path and said support in an arc-shaped path while the sheet and film are maintained in said superposed relation and with a portion of said design moving at the same speed and in the same direction as said film and thereby advancing the superposed film and transparency along said slit,

the transparency being interposed between the slit and sensitized film, and thereby progressively exposing the film to light transmitted from said slit through the transparency.

5 6. The combination of a transparent sheet bearing a design, a photographically sensitized film, a carriage on which said film is mounted, a support on which said transparent sheet is mounted, with said sheet and film parallel and close together in superposed relation, an electric lamp, an enclosure therefor, the walls of the enclosure being formed with an elongated slit, means for moving the carriage in a straight path and in a direction in which the plane of the sheet extends, and means for simultaneously moving the film in an arc-shaped path while maintaining said parallel superposed relation of the sheet and film, said slit being positioned to apply light directly to the transparent sheet during said movement of the carriage.

7. Photographic reproduction apparatus comprising a carriage mounted for straight line movement, a carrier mounted for oscillating movement about an axis perpendicular to the direction of movement of the carriage, means for effecting said movements of the carriage and carrier concurrently, means for holding a sensitized sheet and a design bearing sheet in superposed relation with one sheet mounted on the carriage and the other on said carrier, with the inner faces of said sheets in substantially the same plane perpendicular to said axis, a light source, means enclosing said light source and formed with a slit in the wall of the enclosing means, said slit being positioned adjacent to said superposed sheets and extending transversely of the said direction of movement of the carriage.

8. Photographic reproduction apparatus comprising a carriage, means mounting the carriage for straight line reciprocating movement, a carrier mounted for oscillating movement about an axis perpendicular to the direction of movement of the carriage, means for driving the carriage and carrier, gears interconnecting the carriage and the carrier for causing their simultaneous movement, means for holding a sensitized sheet and a design bearing sheet parallel and close together in superposed relation with one sheet attached to the carriage for straight line movement therewith and the other sheet attached to the carrier for oscillating movement therewith, means for directing a beam of light against a restricted area of the design bearing sheet in the form of a narrow elongated strip area extending transversely to the direction of movement of said carriage and whereby the said movement of the carriage and said carrier causes the light beam to traverse said sheets.

9. Photographic reproduction apparatus comprising a carriage, means mounting the carriage for straight line reciprocating movement, a carrier mounted for oscillating movement about an axis perpendicular to the direction of movement of the carriage, gears interconnecting the carriage and the carrier for causing their simultaneous movement, means for holding a sensitized sheet and a design bearing sheet in superposed relation with one sheet attached to the carriage for straight line movement therewith and the other sheet attached to the carrier for oscillating movement therewith, an electric lamp, a wall of said enclosure having a slit therein positioned to extend across the superposed sheets transversely to the direction of movement of the carriage.

10. Photographic reproduction apparatus comprising a carriage mounted for horizontal reciprocating movement, a rack bar connected to and extending lengthwise of the carriage, a carrier mounted for oscillating movement about a vertical axis, a gear segment connected to the carrier for oscillating movement therewith about said axis and running in mesh with said rack, means for holding a sheet on the carrier and a sheet on the said carriage with the sheets superposed and extending in a horizontal plane, an electric lamp, means providing a slit through which light is transmitted from said lamp, said slit being in juxtaposition to said superposed sheets and extending transversely of the rack and gear substantially at their point of tangency.

11. The method of photographically reproducing a design in a modified or distorted form, which method comprises superimposing a sensitized sheet and a sheet consisting of a transparency bearing said design, causing said sheets to traverse a beam of light projected through a narrow slit close to said sheets and extending transversely to the direction of movement of said sheets and thereby exposing the entire design progressively to the light beam, the movement of both sheets at a point in said light beam being in the same direction and at the same speed throughout the said exposure, and gradually shifting the angular position of one sheet relative to the other during said exposure.

12. The method defined in claim 11, one said sheet moving in a straight line during said exposure and the other sheet moving in an arc-shaped path.

13. The method of photographically reproducing a design in a modified or distorted form, which method comprises superimposing a sensitized sheet and a sheet bearing said design, causing said sheets while superimposed to move across a light beam in the form of a narrow slit extending transversely of the direction of movement of the said sheets with one said sheet moving in an arc-shaped path such that all portions of the sheet while crossing said slit are moving in a direction substantially perpendicular to the slit and with the other sheet moving in a straight path, the portions of both said sheets crossing a predetermined point in said slit, moving in the same direction and at the same speed at said point.

14. The method defined in claim 13, the sheet bearing said design being the one moving in the arc-shaped path, the other sheet moving in a straight path.

15. The method defined in claim 1, the sensitized sheet moving in a straight line direction and the design bearing sheet moving in an arc-shaped path.

16. The method of photographically reproducing a design in a modified form, which method comprises superimposing a sensitized sheet and a sheet consisting of a transparency bearing said design, said sheets having their inner faces in substantially the same plane, applying to a restricted area of the design-bearing sheet a beam of light, said beam at said area being in the form of a narrow strip extending across the sheets, causing a relative movement of the light beam and the sheets in a predetermined direction transverse to that in which the beam extends across the sheets, and by said relative movement exposing the entire design progressively to the light beam and thereby producing a photographic exposure of the sensitized sheet to the said design, and relatively moving, in said predetermined direction, the portions of the sheets at and while crossing the light beam, and with a differential variation in the velocities of the said portions of the sheets crossing the light beam, the difference in velocities at different points in the beam being proportional to the distances of such points from a predetermined point in the beam, thereby modifying the form of the design exposure on the sensitized film relative to the design on said design-bearing sheet.

17. The method defined in claim 16, the relative movement of the said predetermined point and said sheets being such that the said point traverses one sheet in a straight median line extending across the sheet, the velocity of the design-bearing sheet being greater on one side of said median line than that of the sensitized sheet, and on the opposite side of said median line less than that of the sensitized sheet.
